UNITED STATES PATENT OFFICE.

HERMAN R. FREUND, OF BROOKLYN, NEW YORK, ASSIGNOR TO INTERTYPE CORPORATION, OF NEW YORK, N. Y., A CORPORATION OF NEW YORK.

METAL POT FOR LINE-CASTING MACHINES.

Application filed March 20, 1928. Serial No. 263,195.

The present invention relates to improvements in line casting machines of the general class shown and described in U. S. Patents Nos. 436,531 and 436,532 granted September 16, 1890 to O. Mergenthaler, wherein lines of character-bearing matrices are presented to one face of a mold and a metal pot is brought against the opposite face of the mold and molten metal is injected from the metal pot into the mold cavity and against the character-bearing faces of the matrices to form a type bar or slug having type characters along an edge thereof.

Type bars obtained in this way have been extensively used in the printing art for the production of stereotype matrices from which stereotype plates have been cast for printing or for direct printing from the type bars, but the printing processes more recently used, especially in news paper printing, require the imposition of much heavier impression pressure upon the type bars than the pressure previously used in the making of the stereotype matrices, and it has been found in practice that some of the type bars have a tendency to break down under such increased pressures, especially when a large number of impressions are made, this tendency to break down of the type bars being due to lack of solidity or to a spongy texture of the type bars caused by the presence of air holes or the mixing of air with the molten type metal during the casting of the type bars.

Most of the air which becomes mixed with the molten metal during the casting of the type bars and causes the difficulties referred to, comes from the space in the throat of the metal pot between the surface of the metal therein and the mouth-piece which fits against the mold, this space filling with air as the molten metal recedes to its normal level following each casting operation, and when the molten metal is injected into the mold for the next casting operation, such body of air is forced into the casting cavity of the mold in advance of the metal being injected, and the relatively rapid force of the injected stream of metal results in a mixture more or less, of air and metal in the mold cavity, thus rendering portions of the type bar spongy and hence weak structurally, and also forming imperfections in the type face of the bar which if present will produce imperfections in the printed or other impressions made from such type bars.

The primary object of the present invention is to avoid such faults and imperfections in the type bars and to enable type bars to be produced which are capable of withstanding the increased impression pressures now used in stereotyping processes and which will produce more perfect printed or other impressions. According to the present invention, the air contained in that portion of the width of the metal pot throat which is beyond the length of the mold cavity in use is excluded from the mold cavity during the injection of metal therein, the portion of the metal pot throat above the mean practical working level of the metal therein being divided in width by partitions which extend from the said level of the metal, upwardly to the mouth-piece, the partitions thus dividing this space in the throat into a plurality of separate passages which are spaced apart in the direction of the width of the metal pot mouth-piece. Consequently, when the mold is brought into casting relation with the metal pot mouth-piece, the cavity of the mold, which, in news paper column and most other classes of printing, occupies only a part of the width of the mouth-piece, will be in position to receive metal from the passages opposite to the cavity while the closed portion or remainder of the mold beyond the end of the cavity in use will block or close the remainder of the passages in the throat, and hence air contained in the latter passages will be held or trapped therein so that it will not be forced into the mold cavity, and the relatively small amount of air which enters the mold cavity from the passages through which the metal enters it can be vented from the mold cavity by the usual means.

Preferably, the passages between the different partitions in the throat of the metal pot are of equal volume and these passages are spaced apart in definite relation to the length of the mold, so that each passage will supply the same amount of metal to each unit length of the mold cavity in use, and the number thereof which are closed will be determined by the length of the mold cavity used.

The present invention also provides a metal pot mouth-piece having metal injecting ori-fices and the metal directing walls of which are so formed that the molten metal will be projected into the mold cavity in streams which spread in directions longitudinally of the cavity and join or meet one another at

points sufficiently far in advance of the character faces of the matrices as to insure complete filling out of the type face of the type bar with metal free of air holes or other imperfections, it being understood that the solidity of the type bar structure directly under the type face is of major importance to counteract the heavy pressure above mentioned.

To these and other ends the invention consists in certain improvements and combinations and arrangements of parts all as will be hereinafter more fully described, the features of novelty being pointed out particularly in the claims at the end of the specification.

15 In the accompanying drawings:—

Fig. 1 represents a section taken vertically through the casting mechanism of a line casting machine of the general class hereinbefore referred to, the metal pot being constructed in accordance with the present invention;

20 Fig. 2 represents a transverse section taken on the line 2—2 of Fig. 1 and looking in the direction of the arrows;

Fig. 3 represents a section on an enlarged scale taken on the line 3—3 of Fig. 1; and

25 Fig. 4 represents a section taken on the line 4—4 of Fig. 3.

Similar parts are designated by the same reference characters in the several figures.

30 The preferred embodiment of the invention is shown in the drawings wherein 1 designates generally the metal pot which may be similar to those commonly used in machines of the general class referred to, the pot comprising a well 2 which contains the metal used in casting the type bar, the metal being maintained in a molten state by a suitable burner beneath the pot and the pot containing a plunger 3 which is forced downwardly at appropriate times to force some of the molten metal through a throat 4 upwardly and forwardly to a mouth-piece 5, the latter having a metal-tight fit against one side of a mold which is composed usually of a cap 6, a body 7 and interposed liners 12 and 12^a which form a slot or cavity 8 in which the body of the type bar is cast, the opposite face of the mold being closed during the casting operation by a line of matrices 9 which bear type characters in their edges which correspond with those to be formed on the type bar. Normally, the molten metal in the metal pot and in the throat 4 is at a level between the upper and lower levels A and A', for instance, at the mean practical working level indicated at A'', the metal in the throat 4 receding to the level of the metal contained in the well 2 when the plunger 3 rises following completion of each casting operation. As the metal recedes in the throat 4, air is drawn into the throat, so that prior to each casting operation, the throat above the metal therein will be filled with a body of air.

Usually the throat 4 is of a width which increases or flares laterally so that its width

at the mouth-piece 5 is approximately equal to the length of the longest mold cavity to be used in the machine, and heretofore, this entire body of air has been forced into the casting cavity in the mold by the advance 70 of the metal under the action of the plunger 3, incident to each casting operation, and the introduction of this large amount of air into the mold has resulted in the mixing of the air with the injected molten metal, the 75 type bars thus produced having porous or spongy portions which weakened the type bars structurally so that the weakened portions were liable to cave in under the increased impression pressures used in the "dry 80 mat" printing process, and furthermore the mixing of the air with the portion of the metal forming the type face of the type bars produced imperfections therein and in the impressions obtained from such type bars. 85 Moreover, most printing calls for the use of a mold cavity the length of which is equal to only one half or less of the width of the metal pot throat, and the forcing of the large body of air from the entire width of the 90 metal pot throat into a mold cavity of such length increases the difficulties of producing type bars free from spongy or porous portions and from imperfections in the character-bearing edge thereof.

95 According to the present invention, the throat of the metal pot may be made of substantially the usual full width, but the width of that portion of the throat from the practical working level of the metal therein to the mouth-piece is divided by a number of partitions 10 into a number of separate passages 11 which lead from the said level to the mouth-piece 5. The partitions are preferably so spaced that the passages 11 are of 100 equal width, and each of the passages 11 will correspond with a unit length of the mold cavity used, but other proportional relationships between the spacing of these passages and the mold cavity may be used, if 105 desired. For example, if a mold is used which has a cavity of maximum or full length, all of the passages 11 will serve for the injection of metal into the cavity as the full length mold cavity will extend to the full 110 width of the metal pot throat and all of the passages 11 will communicate with the mold cavity but when a mold is used which has a cavity of a length equal to one half or less of the width of the metal pot throat, as is 115 shown in Figure 3 and which is most frequently the case in the use of line casting machines, only a fraction, such as two of the passages 11 will communicate with the mold cavity and serve to supply metal thereto, the remaining passages 11 beyond the mold cavity being opposite to and closed by the portion 12 of the mold beyond the cavity 120 therein and which is usually composed of an imperforate or solid liner which is in 125 130

terposed between the cap 6 and the body 7 of the mold and defines the length of the mold cavity. Irrespective of the length of the mold cavity however, it is intended that 5 each passage 11 may correspond to a definite unit of length of the mold cavity in use so that the metal will be introduced substantially equally or uniformly throughout the length of the cavity, it being preferable 10 to proportion the passages 11 so that each passage corresponds with six ems in the length of the mold cavity.

By providing the multiple separate passages extending from the metal level to the 15 metal pot mouth-piece, as described, the length of the type bar casting cavity in the mold presented to the mouth-piece of the metal pot determines the number of passages which will conduct the metal to the mold 20 cavity and the remainder of the passages will be closed by the liner 12 of the solid portion of the mold beyond the cavity therein. In consequence, when the molten metal in the 25 metal pot throat rises under the action of the plunger to cast a type bar in the mold cavity, the lower ends of the passages 11 not in communication with the mold cavity will be sealed by the rising metal and the air contained in these passages will be trapped there- 30 in so that this air cannot enter the mold cavity, while at the same time rising metal will flow upwardly through the passages 11 which are in communication with the mold cavity and will thus enter the cavity to cast the type 35 bar therein, the relatively small volume of air from these latter passages being vented from the mold cavity by the usual mold venting means.

The metal pot mouth-piece 5 which may be 40 fitted in the usual manner upon the metal pot throat and which makes actual contact with the mold is provided with orifices 13 which register with the respective passages 11. These orifices are preferably formed with 45 metal directing walls which insure proper distribution of the molten metal during its injection into the mold cavity. The upper and lower walls 14 and 15 of each orifice are convexed so that they are flared at their metal-receiving ends and are constricted so that 50 they extend parallel or substantially so at their metal-discharge ends. The vertical walls 16 of these orifices are flared toward their metal-receiving ends and are also flared 55 preferably for a relatively shorter distance at their metal-discharge ends. By forming the orifices 13 in this way, the top and bottom walls 14 and 15 of each orifice will direct the metal horizontally in substantially the 60 form of a sheet conforming with the mold slot or cavity 8 while the vertical walls 16 will cause the metal to spread at each side 65 of the orifices in a direction longitudinally of the mold slot or cavity, and the flares of the vertical walls 16 of the orifices are preferably

so formed that the body of metal injected into the mold cavity from one orifice will meet or join with the body of metal injected there- 70 in from the next adjacent orifice at a point removed within the mold cavity from the edge 75 against which the matrix line 9 fits, as is shown diagrammatically in Fig. 3, this mode of injecting the metal into the cavity insuring the removal of all air from the portion of the mold cavity in which the character-bearing edge of the type bar is cast so that no portion of the character-bearing edge of the type bar will be spongy or porous. The air which is displaced from the mold cavity by the injected metal may be vented therefrom in the 80 usual or any other suitable way, this air being vented from the mold cavity in the present instance by the usual shallow grooves 17 which are formed vertically in the mold-engaging face of the mouth-piece 5, these 85 grooves providing direct exit of the air to the atmosphere.

The invention is shown in the present instance in conjunction with a mold of the conventional or usual well known class having 90 a slot-shaped cavity to form the usual solid-body slug or type bars, but it will be understood that the invention may be used, with similar advantage, in conjunction with other forms of molds used in machines of this class, 95 such for example, as recessed molds of the class shown and described in Letters Patent No. 1,210,078 granted on Dec. 26, 1916, to J. Keenan. The reduction in the amount of air entering the mold from the throat of the 100 metal pot, as accomplished by the present invention, enables the mold to be effectually filled with metal so that the type-bearing edge of the type bar will be cast substantially free of imperfections and this and other portions of the type bar will be substantially 105 free of spongy or similar weakened portions. It will be understood that in each case, the orifices 13 in the mouth-piece of the metal pot will be on the level with the mold liner 110 which spaces the cap from the body of the mold and determines the length of the mold cavity, and that these orifices will be sufficiently small vertically that those orifices opposite to the mold liner will be closed 115 thereby, so that the length of the mold cavity above will determine how many of the orifices will inject metal, and the orifices closed by the liner will not discharge metal. The orifices 13 are in non-communicating relation 120 with one another at the surface of the mold-engaging face of the mouth-piece, and this face is plane-surfaced, as shown, to fit closely against the correspondingly surfaced rear face of the mold, to form a metal tight joint 125 therewith.

I claim as my invention:—

1. A metal pot for line casting machines having a throat for conducting metal upwardly from the pot to the mold-engaging 130

- face thereof, the space in the throat above the metal level therein being divided into a plurality of separate passages which are spaced in the direction of the width of the throat 5 and extend longitudinally therein from the metal level therein to the mold-engaging face.
2. A metal pot for line casting machines having a throat for conducting metal upwardly therethrough to the mold-engaging 10 mouth-piece, the space in the throat above the metal level therein being divided in the direction of the width of the throat, into a plurality of separate passages which lead from the metal level in the throat to the 15 mouth-piece, and the mouth-piece having separate metal injecting orifices which are in alignment with and extend from the respective passages in the throat to the mold-engaging face of the mouth-piece.
- 20 3. A metal pot for line casting machines having a throat for conducting metal upwardly to the mold-engaging face thereof, the space in the throat above the metal level therein being divided into a plurality of sep- 25 arate metal-conducting passages which are spaced in the direction of the width of the throat and lead upwardly therein from the metal level to the mold-engaging face and are non-communicating throughout their 30 length and at the surface of the mold-engaging face.
4. In a line casting machine, the combination of a mold having a cavity for the casting of type bars therein and a closed portion be- 35 yond an end of said cavity which determines its length, and a metal pot having a throat for conducting metal upwardly to the mold-engaging face of the pot, the space in the throat above the metal level therein being divided 40 into a plurality of separate passages which are spaced in the direction of the width of the throat and extend from the metal level therein to the mold-engaging face, metal-injecting orifices being formed for the respective pas- 45 sages at the mold-engaging face which are out of communication with each other and are positioned so that some of said orifices will be closed by the closed portion of the mold when the latter is brought into casting 50 position while others are in communication with the mold cavity.
5. In a line casting machine the combination of a mold having a liner which determines the length of the casting cavity there- 55 in and a metal pot having a throat for con- ducting metal upwardly from the pot to the mold-engaging face thereof, the space in the throat above the metal level therein being di- 60 vided, in the direction of the width of the throat, into a plurality of separate passages which extend upwardly from the metal level therein to the mold-engaging face and are provided at said face with non-communicat-
- ing metal injecting orifices which are positioned at a height to communicate with the 65 mold cavity and are sufficiently small ver- tically to be closed by the mold liner so that some of said orifices will be placed in communication with the mold cavity and other ori- fices will be closed by the mold liner when 70 the mold and the mold-engaging face of the metal pot are brought into contact.
6. In a line casting machine, the combina- 75 tion of a mold having a plane-surfaced face and a slug casting cavity therein extending from said face, and a metal pot having a plane-surfaced mold-engaging face and a throat for conducting metal upwardly from the pot to the mold-engaging face, the throat being formed with partitions therein which 80 are spaced transversely of the throat and ex- tend upwardly from the metal level in the throat and provide separate passages which are provided at the mold-engaging face with individual metal injecting orifices which are 85 out of communication with each other at the mold-engaging face.
7. A metal pot for line casting machines having a mold-engaging mouth-piece provid- 90 ed with a metal-injecting orifice the top and bottom of which are flared in a direction away from the mold-engaging face and the end walls of which are flared toward the mold- 95 engaging face.
8. In a line casting machine, the combina- 100 tion of a mold having a longitudinal slug casting cavity therein, and a metal pot having a mold-engaging mouth-piece provided with a plurality of metal-injecting orifices spaced longitudinally thereof, the end walls 105 of said orifices being convexed so that said orifices flare in a direction toward the mold- 110 engaging face, said flare being operative to spread the streams of metal injected into the mold so that the streams of metal from adja- 115 cent orifices will meet within the mold cavity at points removed from the portion thereof in which the character-bearing edge of the slug is cast.
9. In a line casting machine, adapted to 120 employ molds having slug-casting cavities therein of different lengths, a metal pot hav- 125 ing a throat for conducting metal upwardly to the mold-engaging face of the pot, the space in the throat being divided into a plu- 130 rality of separate passages which are spaced in the direction of the width of the throat and lead upwardly therein from the metal level to the mold-engaging face, said passages being of equal area and each passage corre- 135 sponding with a definite unit of length of the mold cavity in the mold engaged by the metal pot.
- In testimony whereof I have hereunto set my hand.

HERMAN R. FREUND.
